Primary Examiner — T. Chase Nelson*Assistant Examiner* — Jonathan J. Han(74) *Attorney, Agent, or Firm* — Shook, Hardy and Bacon L.L.P.(57) **CLAIM**

The ornamental design for a shoe midsole, as shown and described.

DESCRIPTION

FIG. 1 is a first side rear perspective view of a shoe midsole showing my design according to a first embodiment; FIG. 2 is a side view thereof;

FIG. 3 is a second side rear perspective view thereof; FIG. 4 is a first side rear perspective view of a shoe midsole showing my new design according to a second embodiment in which the claimed design is shown as having a transparent or translucent surface;

FIG. 5 is a side view thereof; and,

FIG. 6 is a second side rear perspective view thereof. The even-length broken lines show the remainder of the article, are directed to environment, represent unclaimed subject matter, and form no part of the claimed design.

1 Claim, 6 Drawing Sheets(56)
